UNITED STATES PATENT OFFICE

JOHN V. HARDING, OF DETROIT, AND RUDOLPH DE BOER, OF GRAND RAPIDS, MICHIGAN,
ASSIGNORS TO METALCRAFT HEATER CORPORATION, OF GRAND RAPIDS, MICHIGAN,
A CORPORATION OF MICHIGAN

HOT WATER HEATER FOR AUTOMOBILES

Application filed July 29, 1929. Serial No. 381,928.

This invention relates generally to heaters for motor vehicles and refers more particularly to those in which hot water from the usual water circulating system for the 15 motor of the vehicle is used as the heating medium.

One of the essential objects of the present invention is to provide a heater of the type described in which air, preferably from 20 the interior of the vehicle body, is drawn into contact with coils containing the hot water and after being heated thereby is forced back into the vehicle body.

Another object is to provide a heater in 25 which the hot water coils are constructed and arranged in such a way that the maximum heating surface is provided for the air and the flow of air around the coils is retarded so that the air will be thoroughly 30 heated before it passes from the heater to the vehicle body.

A further object is to provide a construction in which a single fan advantageously positioned serves as both the means for 35 drawing air from the vehicle body into the heater and for blowing the heated air from the heater into the vehicle body.

A further object is to provide a construction in which the hot air outlet from the 40 heater extends through the dash of the vehicle body and has a flexible connection therewith so that weaving of the vehicle body relative to the motor upon which the heater is mounted will not effect the heater 45 or outlet.

With the above and other objects in view, the invention consists of certain novel features of construction, combinations and arrangements of parts that will be hereinafter 50 more fully described, and particularly pointed out in the appended claims.

In the accompanying drawings:

Figure 1 is a fragmentary elevation of a motor vehicle with a heater embodying 55 our invention applied thereto;

Figure 2 is a fragmentary side elevation of the heater unit;

Figure 3 is a section on the line 3-3 of

Figure 2;

Figure 4 is an enlarged fragmentary pers-

pective view of one of the hot water coils;

Figure 5 is a top plan view of the construction shown in Figure 1;

Figure 6 is an enlarged vertical sectional view of the heater and dash showing the 55 flexible connection between the heater shell and collar in the dash;

Figure 7 is a view similar to Figure 1 but showing a slightly modified construction;

Figure 8 is a view similar to Figure 1 but showing another modification in perspective;

Figure 9 is a view similar to Figure 1 but showing a further modification in perspective.

In the accompanying drawings we have illustrated a conventional form of automobile in which 1 is the motor or engine block having suitable cylinders 2 and a water jacket 3 therefor, 4 is the radiator, 5 is the water pump, and 6 and 7 respectively are the hose connections between the radiator and water jacket, and 8 is the body having a dash 9 provided with a rearwardly extending depression 10.

Referring to our heating apparatus, 11 is a pipe for receiving air from the vehicle body 8, 12 is a blower for receiving air from the pipe 11, 13 is a heating unit for receiving air from the blower and adapted to discharge heated air into the vehicle body. As shown, the pipe 11 is located above the block 1 at one side of the heater unit 13 and extends through the dash 9. The rear 85 end of the pipe terminates just inside of the dash and is provided with a peripheral flange 13'. The blower 12 includes a suitable fan (not shown) and a shell or casing 14 therefor. Preferably this casing is located on a bracket 15 secured to the engine block and has one side connected to the forward end of the pipe 11. A motor 16 for actuating the fan is mounted upon the opposite side of the casing 14 and has suitable live and ground wires 17 and 18 respectively. The live wire 17 may be connected to any live wire on the instrument board of the vehicle body, and includes a controlling switch such as 19 on the instru-

60

100

ment board. The ground wire 18 may be connected to any metal part of the vehicle.

The heater unit 13 comprises a shell or casing 22 and a plurality of hot water coils 23 within said shell. Preferably the shell 22 is mounted upon the engine block and extends longitudinally thereof between the blower 12 and the depressed portion 10 of the dash. The forward end of the shell is 10 tapered and is connected to the blower casting 14 while the rear end of the shell is open and is received in a metal collar 24 secured to the base 25 of the depression 10 of the dash. Preferably a felt washer 26 15 is placed between the shell 22 and the collar 24 so as to permit movement of the shell relative to the collar or vice versa upon movement of the body relative to the motor block, and to prevent vibration and noise, especially during such relative movement. In the present instance, the coils 23 are formed of tubing or piping and are arranged longitudinally of the shell in cone formation with the apices of the cones meeting 25 at the center of the shell, as illustrated in Figures 2 and 3. Preferably the tubing of the coils is provided with fins or disks 30 that serve as heat conductors and retard the flow of air through the shell. Thus with 30 this construction the air will be retarded as it flows through and around the coils and will thereby be heated thoroughly before it passes from the shell to the interior of the vehicle body. Preferably both the 35 intake and outlet portions 31 and 32 of the tubing are at the rear end of the shell and may be connected to suitable parts such as the hose connections 6 and 7 respectively of the usual water circulating system.

40 In Figure 7 we have shown a slight modification in which the blower 40 is secured upon the forward side of the dash 9 and is connected to the forward end of the heater shell 22 by a pipe 41 supported by a bracket 45 42 upon the motor block. With this construction the motor 43 for the blower fan is secured upon the forward face of the blower casing and is adapted to draw air from the interior of the vehicle body through 50 an opening 44 in the dash to the casing and to force such air through the pipe 41 and heater shell 22 back to the interior of the vehicle body. Otherwise, the construction and function of parts are the same as that 55 set forth in Figures 1 to 6 inclusive.

In Figure 8 we have illustrated another 60 modification in which the heater shell 50 extends across the top of the motor block in substantially parallel relation to the dash 9 and is provided with tapered end portions 51 and 52 respectively. Moreover, a bracket 53 secured to the forward side of the dash 9 extends between and serves as a common support for both the blower 54 and motor 65 55. With this construction a circular hole

56 is cut in the dash 9 to permit air from the interior of the vehicle body to be drawn through the dash into the blower. A pipe 57 connected to the blower and tapered end 52 of the heater shell conducts the air from the vehicle body to the heater, and the other tapered end portion 51 of the heater shell is received in a collar such as 24 in the dash and serves to conduct the warm air from the heater to the interior of the vehicle body. A felt washer such as 26 is also used between the end portion of the shell and the collar as a vibration and noise eliminator. Otherwise the construction and function of parts are the same as in Figures 1 to 6 inclusive.

In Figure 9 we have illustrated still another modification in which the heater shell 60 is similar to the shell 50 illustrated in Figure 8, but extends forwardly from and at substantially right angles to the dash 9. As shown the rear end portion 61 of the shell is received in a collar 62 in the dash and is cushioned therein by the felt washer 63, while the forward end portion 64 is connected by a clamp 65 to the outlet end of a blower 66 supported upon a bracket 67 secured to the engine block. Thus with this construction the heater and blower are supported by the collar 62 and bracket 67. 95 Moreover, the pipe 68 for conducting air from the interior of the vehicle body to the blower 66 is received in a collar 69 in the dash and comprises several sections, including an elbow 70. Preferably this elbow and the rear section 71 of the pipe have a slip joint that compensates for movement between the heater and the dash. Otherwise, the construction and function of parts are substantially the same as those illustrated 100 in Figures 1 to 6.

While it is believed that from the foregoing description the nature and advantages of the invention will be readily apparent, we desire to have it understood that we do not limit ourselves to what is herein shown and described and that such changes may be resorted to when desired as fall within the scope of what is claimed.

What we claim as our invention is:

1. A heater for motor vehicles including a tubular shell having an inlet and an outlet for air, and means for heating air as it is received in said shell from said inlet including a core opening toward the air inlet and formed of coils of tubing.
2. A heater for automobiles including a tubular shell, and means for conducting a heating medium through the shell, including coils arranged longitudinally of said shell in cone formation with the apices of the cones meeting at the center of the shell.
3. A heater for motor vehicles including a shell in which air from a suitable source is adapted to be heated, and means for heat-

ing the air within the shell, including coils containing a heating medium and arranged in cone formation.

In testimony whereof we affix our signatures.

JOHN V. HARDING.
RUDOLPH DE BOER.
